COMBINED AMPLIFIER AND TAPE RECORDER

Ippei Kurihara, Osaka, Japan, assignor to Matsushita Electric Industrial Co., Ltd., Osaka, Japan

Filed June 4, 1970, Ser. No. 23,310

Claims priority, application Japan Dec. 10, 1969

Term of patent 14 years

Int. Cl. D14—03

U.S. Cl. D26—14

FIG. 1

FIG. 2

FIG. 3

FIG. 1 is a top, front and right side perspective view of a combined amplifier and tape recorder showing my new design;

FIG. 2 is a rear and left side perspective view thereof, and

FIG. 3 is a right side elevational view thereof.

Portions of the drawing figures are diagonally lined to indicate transparency, and portions are shaded to indicate contrast in appearance.

I claim:

The ornamental design for a combined amplifier and tape recorder, as shown and described.
